TUNNEL NOZZLE FOR RECTANGULAR COKE OVENS

Filed May 27, 1927

UNITED STATES PATENT OFFICE

ALEXANDER S. KNOWLES, OF CHICAGO, ILLINOIS, ASSIGNOR TO TAR & PETROLEUM PROCESS COMPANY, OF CHICAGO, ILLINOIS, A CORPORATION OF ILLINOIS

TUNNEL NOZZLE FOR RECTANGULAR COKE OVENS

Application filed May 27, 1927. Serial No. 194,581.

My invention relates to means for distributing the air and waste heat in each flue of a rectangular, sole-fired, coke oven, heated by a plurality of independent sole combustion flues arranged beneath the sole of the oven and more particularly to a plurality of tunnel nozzles for each flue for supplying and distributing a portion of the air from some of the regenerators to the combustion flues and for discharging waste heat gases from said flues to other regenerators.

Rectangular ovens in which the oven sole is of substantially rectangular shape, form a class of ovens having broad soles, the ovens being heated from beneath the sole. In such ovens, the admission of atmospheric air into the charge is excluded and the by-products and coke are obtained from the coal by heating the broad sole of the oven.

In my Patent No. 1,635,280, a rectangular, sole-fired coke oven is shown in which separate parallel and adjacent sole combustion flues are used for heating the oven chamber and in which the air may be preheated and supplied periodically, at intervals, by means of individual regenerators for each flue.

One of the objects of my invention is to provide each combustion flue of a rectangular oven with a plurality of distributing tunnel nozzles for supplying a portion of the air from one of the regenerators to the flue and for discharging waste heat gases from the said flue to the other regenerator connected with the flue.

With the above and other objects in view, my invention consists in the parts, improvements and combinations more fully pointed out hereinafter.

Referring now to the drawings:

Figure 1, shows a longitudinal cross-section through the oven when provided with a pair of distributing tunnel nozzles in each of the combustion flues of the oven.

Figure 2, is an enlarged longitudinal detail section showing the adjustable tunnel nozzle.

Figure 3, is a detail cross-section on line 3-3 of Figure 2, showing the tunnels in place in the flues.

Figure 4, is a perspective view of one of the sections of the tunnel nozzle.

The coke oven illustrated in the drawings will first be briefly described.

In the drawings 1 indicates the flat tops of the oven supplied with charging openings 2, for supplying coal to the oven, the by-products of gas being taken off by standpipe 3. Each front of the oven chamber is provided with a door 4, 5.

Under each oven sole extends a plurality of separate and independent combustion flues 10. The sole of the oven chamber includes the top of the combustion flues and comprises a plurality of silica bricks 11, with feet 12, resting on the partition walls 13 between the flues. A floor 15, extends between the combustion flues and the regenerators, thus taking up the heat from the flues and supplying it in part to the regenerators.

As illustrated a plurality of air regenerators for preheating the air supplied to the combustion flues, is provided there being two hairpin regenerators which alternately and periodically supply air to and receive the products of combustion from each heating flue. These air regenerators are provided with a regenerator checkerwork 27, and each regenerator comprises a pair of flues 21, 22 separated by a division wall 30, the regenerator extending below and parallel to the combustion flue above it. Air is supplied to the regenerators by separate air admission pipes 31, provided with openings, closed by removable plugs 31^a. Waste heat discharge pipes 32, are also provided controlled by slide dampers 32^a.

Gas is supplied to the combustion flues by separate gas pipes 33, one for each combustion flue. Preheated air reaches the combustion flue from its regenerator thru port 34, the amount of opening of the port being adjustable by slide brick 35. Removable brick 36, in front of the slide brick permits adjustment of the latter. Inspection ports 37, having removable plugs (not shown), permit the inspection of the regenerators.

Coming now to my invention, means are provided for distributing the air and waste heat gases in each flue so as to provide increased heating in the flues toward the middle of the oven and so as to also decrease the heating

at the ends of the oven, thereby producing a uniform heating of each flue in long ovens.

As illustrated, two or more distributing tunnel nozzles 45, are provided, one or more for each end of each flue. The shape of the nozzles may be varied and they are preferably made of refractory material. As shown each nozzle consists of a series of U-shaped sections 46. These sections may be joined as at 10 47, and one or more sections may be used, the nozzle being correspondingly lengthened or shortened as desired. The front end of each nozzle is closed by the end wall 48 of the section and the rear end 49, i. e. the end at the interior of the flue, is open. By making the nozzle U-shaped with an open bottom, air may be supplied to the nozzles thru supplementary openings 50, 51, made in the silica bricks 15, separating the regenerator from the sole of 15 the oven. Slide dampers (not shown) may be provided for adjusting the openings 50, 51.

The roof of each tunnel nozzle section is preferably provided with an auxiliary opening at 25 52, permitting the discharge of air or the receipt of waste heat gases, when the oven is in operation. The nozzle may be adjusted so as to assume various positions along the flue sole, one such position being shown in full lines and another in dotted lines in Fig. 2, 30 this being done by means of an adjusting rod inserted by removing bricks 35, 36, at the end of the flue.

As shown when one nozzle at one end of a flue is receiving and distributing preheated air for combustion coming through the opening 51, the other nozzle is receiving some of the waste gas and delivering it through the opening 50, into the regenerator. On reversal 35 of the oven, the flow of air and waste gas is reversed through the regenerators, the openings and the nozzles.

It will be observed that gas is alternately admitted through the usual burner pipes 33, at the end of the flue. The amount of air for 45 combustion admitted through the air opening 34, at the end of the flue, may be regulated and depends upon the length of the flue and the character of the gas to be burned. The intensity of the heat at the outer end of the flue may thus be regulated and reduced. The excess, unburnt gas is subsequently burned by combining with the air for combustion which enters the nozzle through the supplementary opening. The movable nozzle distributes this air for combustion toward the center of the flue, to more uniformly heat the flue lengthwise. While this is going on, the nozzle in the other end of the flue receives 50 a part of the waste gas and conveys it through its supplementary opening at the other end, where it passes into the regenerator, the balance of the waste gas leaving the flue and entering the regenerator thru the opening 34, 55 provided at the outer end. The flame is thus

lengthened and the intensity of the heat at the outer end of the flue is reduced.

Where low heat value gas such as producer or blast furnace gas is available, the regulation of the long flame resulting therefrom permits the use of one or more tunnel nozzles and opening or openings at each end of the flue. When using high heating value gas, such as that produced from high volatile coal making an intense, short flame, two or more tunnel nozzles at each end may be used with suitable 70 75 openings connecting the nozzles to the regenerators.

Having thus described the invention and its operation, it will be understood that 80 changes may be made in carrying the invention into effect, without departing from the principle thereof.

What I claim is:

1. In a rectangular, sole-fired coke oven, 85 provided with a plurality of sole combustion flues, arranged under the sole of the oven for heating it, and a plurality of regenerators connected with said flues for alternately supplying preheated air to opposite 90 ends of each of said flues, the combination with the sole combustion flues of a plurality of supplementary distributing means arranged in two sets within each flue and communicably connected with the regenerators; 95 each set adapted to alternately receive and supply a portion of the air from some of the regenerators to the flues and to receive and discharge waste heat gases from the said flues to the regenerators, and means for supplying gas to opposite sides of the combustion flues.

2. In a rectangular, sole-fired coke oven provided with a plurality of sole combustion flues arranged under the sole of the oven for heating it, a plurality of regenerators for alternately supplying preheated air to said flues and a floor separating the regenerators from the flues provided with supplementary openings, the combination with said sole 105 combustion flues of a plurality of distributing tunnel nozzles, the said openings and tunnel nozzles cooperating to supply a portion of the preheated air from some of the regenerators to the flues and to discharge waste heat gases from the said flues to other regenerators.

3. In a rectangular, sole-fired coke oven, provided with sole combustion flues, regenerators beneath said flues, there being a pair 120 of regenerators for each combustion flue, and a floor separating the regenerators from the flues, the said floor being provided with supplementary openings, the combination with said flues of a plurality of tunnel nozzles, the said nozzles each comprising a sectional, open-bottom tunnel, each nozzle being closed at its front end and open at its rear end, the supplementary openings and nozzles cooperating to supply a portion of 125 130

the preheated air from one of the regenerators of the pair to its flue and to discharge waste heat gases from the said flue to the other regenerator of the pair.

4. In a rectangular, sole-fired coke oven, provided with sole combustion flues, regenerators beneath said flues, and a floor separating the regenerators from the flues, the said floor being provided with supplementary openings, the combination with said flues, of movable tunnel nozzles, the said nozzles each comprising one or more sectional, open-bottom tunnels provided with auxiliary openings, each nozzle being closed at its front end and open at its rear end, the supplementary openings and nozzles cooperating to supply a portion of the preheated air from some of the regenerators to the flues and to discharge waste heat gases from the said flues to other regenerators.

In testimony whereof, I have signed my name to this specification.

ALEXANDER S. KNOWLES.
